[57] CLAIM

The ornamental design for a child's rocker, as shown and described.

DESCRIPTION

FIG. 1 is a right-front perspective view of a child's rocker showing my new design;

FIG. 2 is a front perspective view;

FIG. 3 is a right side perspective view;

FIG. 4 is a rear perspective view;

FIG. 5 is a left side perspective view;

FIG. 6 is a top perspective view; and,

FIG. 7 is a bottom perspective view thereof.

FIGS. 6 and 7 have been drawn to a larger scale with respect to FIGS. 1 through 5.

FIG. 1

FIG. 2

FIG. 3

—FIG. 4

—FIG. 5

—FIG. 6

—FIG. 7
